ATTORNEY.

UNITED STATES PATENT OFFICE.

PHILIP H. HARRIS, OF BRONX, NEW YORK.

BUTTON.

Application filed July 25, 1928. Serial No. 295,269.

This invention relates to a process of making buttons for articles of clothing from strips of material such as leather or the like.

The principal object of the invention is to provide a device of this character made from strips of leather or the like and so arranged that when the said strips are bent over each other a semicircular shaped button will be formed.

Another object of the invention is to provide the strips of leather or the like from which the button is made with metal reinforcing elements for the purpose of keeping the formed button in a set position.

With the above and other objects in view as will be hereinafter apparent, the invention consists in general of certain novel details of construction and combination of parts hereinafter fully described, illustrated in the accompanying drawings and specifically claimed.

In these drawings like parts are designated by like reference characters throughout the specification.

Figure 1 is a top view of the finished button.

Figure 2 is an edge view thereof.

Figure 3 is a top view of the relative position of the parts which make up the button showing them in an unassembled position.

Figure 4 is a similar view as Figure 3 showing the button in a partly assembled position.

Figure 5 is a section on line 5—5 of Figure 3.

Figure 6 is a view of one of the members which make up the button.

Figure 7 is a top view of one of the disks.

Figure 8 is a perspective view of the eye for securing the button to an article of clothing.

Figure 9 is a view of the metal strap.

Figure 10 is a modified form of the body member of the button.

Figure 11 is another modification thereof.

The main part of the button is composed of a pair of leather strips 1 and 2 placed at right angles to each other as shown in Figure 3. The ends of the strips are provided with slits 3 forming two portions 4 and 5. Fas-

tened to the opposite ends of the strips or to the portions 4 are metal straps 6. Each of the strips 1 and 2 are provided with a hole 7 in the center so the eye 8 for fastening the button to an article of clothing can pass through.

As shown in Figure 5, placed above the strip 1 is a disk 9 having a slot 10 in the center for the shank 11 of the eye 8 to pass through. Placed above the top of the eye is another disk 12. The purpose of the disks 9 and 12 is to securely position the eye and to provide some material for the interior on which to build up the button and give it its semicircular profile.

The metal straps are fastened to the leather strips 1 and 2 in the following manner. As noted in Figure 9 the straps have narrow portions 13 at the ends. These narrow portions pass through slots 14 cut in the leather strips and are bent over forming a loop as seen in Figure 5 thus firmly securing the metal and leather together. The straps are made of nonelastic metal so when they are bent in place they will stay in that position permanently.

In assembling and finishing the button the various elements are positioned as shown in Figure 5 and the leather strips 2 are then bent over as shown in Figure 4. The leather parts may be soaked in water to make them pliable. The next step resides in bending over the strip 1 in the same manner as with the strip 2 but placing the end 15 of strip 1 underneath the portion 16 of strip 2 and the end 17 of strip 1 underneath the portion 18 of strip 2. This arrangement will interlock the ends and give the surface of the button the novel and ornamental effect as shown in Figure 1. It might be said here that the purpose of slitting the ends of the leather strips is to allow the portions 5 to be tucked underneath the portions 4 so as to increase the thickness of the body of the button.

The next step is to place the button in a powerful die and be pressed into the desired shape. Due to the novel manner of interlocking the ends of the leather strips and the introduction of the metal straps the button will take a permanent set. The various thickness of leather in the center of the button will form a foundation on which to build up the button and give the semicircular profile.

The main or body member 19 of the button can be made of one piece of material as shown in Figure 10 and provided with extensions or arms 20. Also instead of having the strips of leather 1 and 2 made of one piece they can be made in two half sections 21 and 22 and sewed together by a stitch 23.

It will thus be seen that I have provided a novel method of making a button from leather or the like which has a pleasing appearance and is substantially indestructible.

5 The foregoing disclosure is to be regarded as descriptive and illustrative only, and not as a limitation of the invention, of which obviously an embodiment may be constructed including many modifications without departing from the general scope herein indicated and denoted in the appended claims.

Having thus described my invention, I claim:-

1. In a method of making a button comprising two leather strips placed substantially at right angles to each other and having a foundation in the center, folding over the ends of the said strips over the said foundation, and subjecting the blank thus formed 15 to a relatively high pressure between highly finished dies so as to give the finished button a permanent set.

2. In a method of making a button comprising two leather strips placed substantially at right angles to each other and having a circular foundation in the center, folding over the ends of the said strips over the said circular foundation, and subjecting the blank thus formed to a relatively high pressure 25 between highly finished dies so as to give the finished button a permanent set.

3. In a method of making a button comprising two leather strips placed substantially at right angles to each other and having a foundation in the center, placing an eye provided with a shank in the center of the foundation and allowing the said shank to protrude through holes in the center of the two leather strips, folding the ends of the 35 said strips over the said foundation and subjecting the blank thus formed to a relatively high pressure in a die for giving the finished button a permanent set.

4. In a method of making a button comprising two leather strips placed substantially at right angles to each other and having a foundation in the center, fastening a reinforcing strap to the end of each leather strip, placing an eye provided with a shank 45 in the center of the foundation and allowing the said shank to protrude through holes in the center of the two leather strips, folding the ends of the said strips over the said foundation and subjecting the blank thus formed to a relatively high pressure in a die for giving the finished button a permanent set.

5. In a button of the class described, two leather strips placed at right angles to each other and provided with a hole in the center of each strip, an eye having a flange passing through said holes, the ends of the said strips being folded over the said flange of the eye, and means for giving the structure a permanent set between dies under high pressure.

6. In a button of the class described, two

leather strips placed at right angles to each other and having a hole in the center of each strip registering with each other, an eye including a flange and shank, said shank protruding through said holes, a metal reinforcing strap attached to the ends of the leather strips, the ends of the said leather strips being folded over the said flange of the eye, and means for giving the structure a permanent set by being subjected under high pressure under suitable dies.

7. In a button of the class described, two leather strips placed at right angles to each other and having a hole in the center of each strip registering with each other, an eye including a flange and shank, said shank protruding through said holes, a metal reinforcing strap attached to the ends of the said leather strips, said ends of the leather strips having slits so the ends of the said straps 70 can pass through and be bent over forming a loop, the ends of the said leather strips being folded over the said flange of the eye, and means for giving the structure a permanent set by being subjected under high pressure 75 under suitable dies.

8. In a method of making a button comprising two leather strips placed substantially at right angles to each other and having a foundation in the center, folding over and 80 interlocking the ends of said strips over the said foundation, and subjecting the blank thus formed to a relatively high pressure between highly finished dies so as to give the finished button a permanent set.

9. In a method of making a button comprising two leather strips placed substantially at right angles to each other and having a circular foundation in the center, folding over and interlocking the ends of the said strips over the said circular foundation, and subjecting the blank thus formed to a relatively high pressure 95 between highly finished dies so as to give the finished button a permanent set.

10. In a method of making a button comprising two leather strips placed substantially at right angles to each other and having a circular foundation in the center, folding over and interlocking the ends of the said strips over the said circular foundation, and subjecting the blank thus formed to a relatively high pressure between highly finished dies so as to give the finished button a permanent set.

11. In a button of the class described, two leather strips placed at right angles to each other and having a hole in the center of each strip registering with each other, an eye including a flange and shank, said shank protruding through said holes, a metal reinforcing strap attached to the ends of the leather strips, the ends of the said leather strips being folded over and interlocked over the said flange of the eye, and means for giving the structure a permanent set by being subjected under high pressure under suitable dies.

12. In a button of the class described, two leather strips placed at right angles to each other and having a hole in the center of each strip registering with each other, an eye including a flange and shank, said shank protruding through said holes, a metal reinforcing strap attached to the ends of the said leather strips, said ends of the leather strips

having slits so the ends of said straps can pass through and be bent over forming a loop, the ends of the said leather strips being folded and interlocked over the said flange 5 of the eye, and means for giving the structure a permanent set by being subjected under high pressure under suitable dies.

12. A button element made from strips of leather and having a metal reinforcing strap running parallel to said strip, said metal strap attached to the opposite end of each of said strips.

13. In a method of making a button comprising a piece of leather having a series of extensions, folding over said extensions towards the center of said piece of leather, and subjecting the blank thus formed to a relatively high pressure between highly finished

dies so as to give the finished button a permanent set.

14. In a button of the class described, a strip of leather having projections, an eye for sewing said button to articles of clothing, said projections bent over and covering the upper portion of said eye and means for giving the structure a permanent set between dies under high pressure.

15. In a device of the class described, a button element made from a piece of substantially circular shape leather or the like and having projections on the periphery of said element, a button sewing element, the said projections adapted to be bent over and retain in place said button sewing element.

In testimony whereof I affix my signature.

PHILIP H. HARRIS.
